HIGHWAY CROSSING SIGNAL SYSTEM

William S. Henry, Coldwater, and Stuart J. Mackey, Rochester, N. Y., assignors to General Railway Signal Company, Rochester, N. Y.

Application January 20, 1931, Serial No. 509,976

15 Claims. (Cl. 246—130)

This invention relates in general to signalling systems, and has more particular reference to a highway crossing signal system of an improved form.

5 In highway crossing signals employing usual interlocking relays, if a train enters one of the usual detector track sections, at one side of a highway at a time when the other detector track section at the other side of the highway 10 is shunted, or de-energized, or open circuited, from any cause whatsoever, the interlocking relay for the side of the entering train is already latched up, and hence the train cannot warn of the danger due to its approach to the highway by energizing the highway crossing signal. In other words, there is no protection afforded 15 by the highway signal against a train approaching the highway under such conditions. The short-circuiting or shunting referred to, of one 20 of the detector track sections, can occur due to a maintainer testing the track circuit, to a sleigh runner or the like over the track rails, or to other means.

One of the objects of the present invention is 25 to protect against a combination of circumstances as pointed out above, whereby to prevent a train from approaching the highway without manifesting its presence by energizing the crossing signal.

30 Further objects, purposes and characteristic features will appear as the description progresses, reference being made to the accompanying drawings, showing, solely by way of example, and in no manner in a limiting sense, two forms 35 which the invention can assume. In the drawings:—

Fig. 1 is a diagrammatic view showing one form of the invention.

Fig. 2 is a fragmentary diagrammatic view, 40 showing structural features of a part of the invention.

Fig. 3 is a diagrammatic view showing a second form of the invention.

Fig. 4 is a diagrammatic view showing a further modification of the invention.

Referring to the drawings, and first to Fig. 1, there is here shown a stretch of single track 50 constituted by track rails 1, separated into insulated blocks A, B and C by insulating joints 2, each of the blocks being supplied with track circuit current as from a battery 3, through a limiting resistance 3¹, and having connected across its other end a track relay, TR¹, TR, TR⁰ respectively.

55 Crossing the track is a highway HW, and for

indicating the approach of a train to the highway, there is provided a flashing light FL, of any usual or desired form, such for example, as that shown in the patent of S. M. Day, No. 1,902,799, granted March 21, 1933.

Controlled through a front point of the track relay connected to the block B, across, and wholly within, which the highway passes, is an interlocking latching relay IR. This relay IR, as shown in Fig. 2, includes two pivoted armatures, 4 and 5, biased by gravity to move downwardly against stops 6 and 7, and held in the full line position, shown in Fig. 2, when armature 8 is energized.

As shown in Fig. 2, contact carrying armatures 9 and 10 of relays TR⁰ and TR¹ respectively, are so positioned with respect to the pivoted armatures 4 and 5 as to be locked against moving to full released position by the armatures 4 and 5, if such armatures are down, and were released prior to the release of armatures 9 and 10 respectively. When de-energized in such circumstances, the armatures of relays TR⁰ and TR¹ move toward full released position, but are prevented from moving far enough to close their back contacts.

Referring again to Fig. 1, the operation of the system is as follows:—Assuming a west bound train entering block A, relay TR¹ releases its contact finger 10 to thereby energize the flashing light FL, through a circuit including one terminal (+) of a source of energy, contact finger 10 and back point of relay TR¹, wires 11, 12 and 13, signal FL, and the other terminal of the source of energy, whereby to cause a flashing signal to be displayed, and warn traffic on the highway of approaching danger.

As the train continues toward the highway, and occupies block B, relay TR releases its armature to thereby de-energize interlocking relay IR, which is normally energized through a circuit including contact finger 14 and front point of TR and wire 15. This permits the latching pivoted armatures 4 and 5, to move under the force of gravity, against their stops 6 and 7. The armature 5 takes a position above armature 10, since armature 10 is already in released position, and hence armature 10 cannot be locked in its released position. The armature 4, however, takes a position beneath armature 9 of relay TR⁰, to thereby lock armature 9 against moving to its full released position.

Upon block A becoming unoccupied, relay TR¹ picks up, to thereby break the energizing circuit for the flashing light FL, traced above. An 110

- energizing circuit, however for the flashing light still exists, since dropping of contact finger 14 of relay TR, completes an energizing circuit for the flashing light FL, which includes contact finger 14 and back point of relay TR, and wires 16 and 13. In this manner, the energization of the flashing relay has not been interrupted, and the locking of the contact finger of relay TR⁰ in raised position has been delayed until the approaching train has entered the block B, which is preferably a relatively short block and possibly just long enough to include highway HW. Furthermore, if the relays TR⁰ and TR¹ be not wound and proportioned so as to allow them, on being energized, to pick up their contact fingers in spite of IR being de-energized and having its contact fingers 4 and 5 down, it is obvious that the above described desirable results still obtain. Thus, the relays can be adjusted so that with relay IR down, it either does, or does not lock the contact fingers of TR⁰ and TR¹ down.
- Upon the train occupying block C, relay TR⁰ is de-energized, but its contact finger 9 cannot move to full released position, since it is latched up by armature 4 of interlocking relay IR. On block B becoming unoccupied, relay TR picks up, to thereby de-energize the flashing light FL, and re-energize the interlocking relay IR. The interlock between the armature 4 and armature 9 continues, however, as the relays are so adjusted that the armature 9, locks 4 down, until block C becomes unoccupied, whereupon relay TR⁰ is re-energized, and raises its armature 9 so as to release the armature 4 and permit all parts to be restored to the normal positions as shown in Fig. 1.
- In this manner a train approaching the highway crossing causes a flashing light in good time to warn highway traffic of the approaching danger, and does not latch up the relay for the approach block on the opposite side of the highway, until the train is practically at the crossing. Should an approaching west bound train de-energize the relay IR, after having de-energized relay TR¹, the relay TR⁰ would be locked up, and if, at this time, an east bound train should occupy the block C, the relay TR⁰ would be de-energized and would release its armature 9, to lock the armature 8 in retracted position, so that, if the west bound train were to back out of the blocks B and A, the east bound train could not manifest its presence by energizing the signal FL. Thus, a train entering block A, for example, to load or unload, and then backing out of the block A, cannot prevent a warning signal being given by a train approaching the highway from the opposite direction, and entering block C.
- Furthermore, should one of the blocks A or C become shunted (say momentarily), as by a sleigh runner, or a crow bar, or the like, or due to a test being made of the track circuit, this cannot lock up the system so as to prevent a train, approaching the highway and occupying the other of these two blocks at this time, from manifesting its presence both at once, and after the first said shunt shall have been removed, by energizing the crossing signal FL.
- The operation of the interlocking or latching relay IR, and the track relays TR⁰ and TR¹, is diagrammatically shown in Fig. 2, from which it can be seen that the interlocking relay can lock either or both of the other two relays against moving to full released position, i. e.,

against closing their back contacts, if the interlocking relay is first de-energized. Furthermore, each of the relays TR⁰ and TR¹ is designed so it can lock the respective cooperating armature of the interlocking relay, in released position, if such relay TR⁰ or TR¹ is de-energized after relay IR has been de-energized and has released its armatures. Also the relays are preferably, although not necessarily (see above) so designed that relays TR⁰ and TR¹, when energized, are able to move their armatures 9 and 10 to attracted position, even though the armatures 4 and 5 of the lock relay IR, be retracted at the time, after which, if relay IR still be de-energized, its armatures 4 and 5 will move to retracted position.

In Fig. 3 is shown a slightly modified form of the invention, in which the interlocking relay IR of Fig. 1, has been replaced by two separate interlocking relays IR¹ and IR². The operation is exactly the same as described above, the change merely substituting, for the relay IR of Fig. 1, which is in effect a double relay having two separate armatures 4 and 5, two separate relays having the armatures 4¹ and 5¹, respectively. By using separate relays, the advantage is obtained of being able to position each interlocking relay adjacent its track relay with which it cooperates and locks, and under certain conditions it may be desirable for economy in wiring and the like, to use the arrangement of Fig. 3 in place of that of Fig. 1.

Referring now to Fig. 4, another form of the invention is shown, wherein, the track is divided, in the same manner as above described, into insulated blocks A, B and C with a highway, HW, crossing the track, and included, in block B. In this form of the invention, the interlocking or latching relay IR has the armatures 4 and 5, for respectively locking the armatures 9 and 10 of track relays TR⁰ and TR¹ of the respective blocks C and A, in the same manner as described above, and illustrated in Fig. 2.

The interlocking relay IR, however, is controlled in a different manner. It has one energizing circuit, as in Fig. 1, including contact finger 14 and front point of relay TR, and wire 15 and 15¹. The relay IR also has a second energizing circuit, including contact finger 16 and front point of relay TR⁰, wire 17, contact finger 18 and front point of relay TR¹, and wires 19 and 15¹. From a consideration of these energizing circuits for the interlocking relay IR, it will be seen that de-energization of the interlocking relay requires, not only that the block B be shunted to thereby de-energize relay TR, but in addition that, simultaneously therewith, one of the blocks A and C also be shunted, to thus break the second circuit, traced just above.

In the form of invention shown in Fig. 4, the short track circuit B, which includes the highway, is made short enough to be spanned by the shortest train encountered.

As in the form of invention shown in Fig. 1, the short circuiting of either of the relays TR¹ or TR⁰, of the approach track sections A and C, does not cause the interlock to function between IR and relays TR⁰ and TR¹ and hence avoids the danger of locking up the system so that a train approaching from the other direction cannot itself manifest its presence when occupying the other approach track section regardless of whether or not the first mentioned approach track section meantime should become unoccupied.

As a further safeguard against dangerous conditions, the arrangement of Fig. 4 cares for a short-circuited or shunted condition of the short track section B. Should a sleigh, or the like, interconnect the rails of section B, this would cause relay TR to release, but would not in itself de-energize the interlocking relay IR, since its second energizing circuit, passing through the front points in series of the relays TR⁰ and TR¹, would be intact. Thus, an approaching train, on entering block A for example, while a sleigh or the like is interconnecting the rails of the block B, de-energizes relay TR¹ to thereby close an additional energizing circuit for the flashing light FL, through a circuit including contact finger 10 and back point of TR¹ and wires 11, 12 and 13, to thereby warn of the approaching danger and continue to warn of this danger after the sleigh shunt in block B has been removed. Had the lock relay IR been de-energized by the shunt across block B, the approaching train on block A could not have closed the circuit through 10, 11, etc., for energizing the signal FL; so that, upon the shunt across B being removed, no warning signal would remain in operation to manifest the presence of the train in block A.

In this form of the invention, the interlocking relay IR should be slow enough on release, to allow the track relay of the approach section to release ahead of it, and if it is not inherently slower in action, it can be made so by any suitable means, such as a short-circuited copper band or the like, as indicated in Fig. 4.

In the system shown in Fig. 4, there is thus provided means for preventing signal failure when an approaching train enters an approach detector track circuit, at the time there is a shunt, across either the other approach track circuit, or across the short track circuit B including the highway. In the case where the system is employed in a cold climate, where sleighs are generally used, with a series of sleighs passing over the highway, and perhaps continuously shunting the track rails of the short track section, it can be seen that the arrangement of Fig. 4 has distinct advantages.

The above described forms of invention therefore provide against a very usual defect in usual systems of this character, wherein the interlock provided, is effective as soon as an approaching train manifests its presence by causing a highway signal to function, and thereby locks the system up to prevent a train approaching from the other direction from manifesting its presence.

The above described systems are of particular advantage in cases where trains approach a crossing for loading or unloading, and then back away from the crossing, the usual crossing signal system in such cases being practically useless, since all the time that the train is on one of the approach track sections, there is no safeguard against a train approaching from the other direction.

In any of the forms above described, it is to be understood that the various relays employed, can, if desired, be indirectly controlled by the track circuits, as by repeating a track relay, and need not be directly connected to the track circuits, as shown solely for the sake of illustration, in this application.

The above specific description of several forms of inventions, has been given solely by way of

illustration, and is not intended, in any manner whatsoever, in a limiting sense. Obviously, this invention can assume many different physical forms, and is susceptible of numerous modifications, and all such forms and modifications, are intended to be included by this invention, as come within the scope of the appended claims.

Having described our invention, we now claim:

1. In a highway crossing signal system for railways, a stretch of single track, a highway crossing the track, a signal, means for automatically energizing the signal upon the approach of a train to the highway from either direction, and means effective upon a closer approach of the train to the highway for preventing the approach of a train from the other direction from controlling the signal. 80
2. In a highway crossing signal system for railways, a stretch of single track, a highway crossing the track, a signal, two initiating means each for automatically energizing the signal upon the approach of a train to the highway from either direction, and means effective only upon a closer approach of the train to the highway for preventing effective operation of an initiating means for thus preventing the approach of a train from the other direction from controlling the signal. 90
3. In a railway highway crossing signal system, in combination, with a highway crossing a stretch of single track, and a signal, an isolated track section at each side of the crossing, and an isolated track section including the highway, signal initiating means for each side section normally responsive to occupancy of its section to energize the signal, and lock means responsive to occupancy of the highway section to prevent the said normal response of any said initiating means that has not already responded 100 from energizing the signal. 105
4. In a railway highway crossing signal system, in combination with a highway crossing a stretch of single track, and a signal, an isolated track section at each side of the crossing, and an isolated track section including the highway, signal initiating means for each side section normally responsive to occupancy of its section to energize the signal, and lock means responsive to simultaneous occupancy of the 110 highway section and one of the side sections to prevent normal responsiveness of any initiating means that has not already responded from energizing the signal. 115
5. In a highway crossing system for railways 120 for use where a highway crosses a railway track, an approach track section wholly to each side of the highway, a center track section including the highway, a warning signal, means for energizing the signal on occupancy of one approach section, and means effective upon occupancy of the center section, for preventing occupancy of the other approach section from energizing the signal until after the said other approach section has been occupied and then vacated. 125
6. In a highway crossing system for railways, 130 for use where a highway crosses a railway track, an approach track section wholly to each side of the highway, a center track section including the highway, a warning signal, means for energizing the signal on occupancy of one approach section, and means effective only upon occupancy of the center section, for preventing occupancy of the other approach section from energizing the signal until after the other ap- 135
7. In a highway crossing system for railways, 140 for use where a highway crosses a railway track, an approach track section wholly to each side of the highway, a center track section including the highway, a warning signal, means for energizing the signal on occupancy of one approach section, and means effective only upon occupancy of the center section, for preventing occupancy of the other approach section from energizing the signal until after the other ap- 145
8. In a highway crossing system for railways, 150 for use where a highway crosses a railway track, an approach track section wholly to each side of the highway, a center track section including the highway, a warning signal, means for energizing the signal on occupancy of one approach section, and means effective only upon occupancy of the center section, for preventing occupancy of the other approach section from energizing the signal until after the other ap-

- proach section has been occupied and then vacated.
7. In a highway crossing system for railways, for use where a highway crosses the railway track, an approach track section wholly to each side of the highway, a center track section including the highway, a warning signal, means for energizing the signal on occupancy of one approach section, and means effective upon simultaneous occupancy of the center section and the said one approach section, for preventing occupancy of the other approach section from energizing the signal until after the other approach section has been occupied and then vacated.
8. In a signal system, a stretch of single track, a highway crossing the track, means dividing the track into insulated sections, a center section wholly including the highway, and an approach section at each side of the highway, a warning signal, a track relay for each section, a control circuit for the signal including, in multiple, back points of the approach section relays, and a latching relay, effective to prevent release of the approach section relays if de-energized before de-energization of the approach section relays.
9. In a signal system, a stretch of single track, a highway crossing the track, means dividing the track into insulated sections including a center section wholly including the highway, and an approach section at each side of the highway, a warning signal, a track relay for each block, a control circuit for the signal including in multiple, back points of the approach section relays, and a latching relay, controlled through a front point of the center section relay, effective to prevent release of the approach relays if de-energized before de-energization of the approach relays.
10. In a signal system, a stretch of single track, a highway crossing the track, means dividing the track into insulated sections including a center section wholly including the highway, and an approach section at each side of the highway, a warning signal, a track relay for each block, a control circuit for the signal including in multiple, back points of the approach section relays, and a latching relay controlled through a front point of the center section relay, and through a separate circuit including front points in series of the approach section relays, which latching relay is effective to prevent release of the approach relays if de-energized before de-energization of the approach relays.
11. In a railway highway crossing signal system, in combination with a highway crossing a stretch of single track, and a signal, an isolated track section at each side of the crossing, and an isolated track section including the highway, signal energizing means for each side section normally responsive to occupancy of its
- section to energize the signal, and lock means responsive to occupancy of the highway section to prevent any said signal energizing means, that has not already responded to energize the signal, from energizing the signal.
12. In a railway highway crossing signal system, in combination with a highway crossing a stretch of single track, and a signal, an isolated track section at each side of the crossing, and an isolated track section including the highway, signal energizing means for each side section normally responsive to occupancy of its section to energize the signal, and lock means responsive to, and not responsive unless, there be substantially simultaneous occupancy of the highway section and one of the side sections to prevent any said signal energizing means, that has not already responded to energize the signal, from energizing the signal.
13. In a railway highway crossing signal system, in combination with a highway crossing a stretch of single track, and a signal, an isolated track section at each side of the crossing, and an isolated track section including the highway, signal initiating means for each side section normally responsive to occupancy of its section to energize the signal, and lock means responsive only to the substantially simultaneous occupancy of the highway section and at least one other section, to prevent the said normal response of any said initiating means that has not already responded from energizing the signal.
14. In a highway crossing system for railways, for use where a highway crosses a railway track, an approach track section wholly to each side of the highway, a center track section including the highway, a warning signal, means for energizing the signal on occupancy of one approach section, and means effective upon the substantially simultaneous occupancy of the center section and said one approach section, for preventing occupancy of the other approach section from energizing the signal until after the said other approach section has been occupied and then vacated.
15. In a highway crossing system for railways, for use where a highway crosses a railway track, an approach track section wholly to each side of the highway, a center track section including the highway, a warning signal, means for energizing the signal on occupancy of one approach section, and means effective only upon the substantially simultaneous occupancy of the center section and said one approach section, for preventing occupancy of the other approach section from energizing the signal until after the said other approach section has been occupied and then vacated.
